Primary Examiner—Cynthia E Ramirez*(74) Attorney, Agent, or Firm*—Levine Bagade Han LLP(57) **CLAIM**

The ornamental design for a trash receptacle, as shown and described.

DESCRIPTION

FIG. 1 is a top perspective view of a trash receptacle, shown with a door in a closed position;

FIG. 2 is a front view thereof;

FIG. 3 is a left side view thereof;

FIG. 4 is a right side view thereof;

FIG. 5 is a top perspective view of the trash receptacle of FIG. 1, shown with the door in an open position;

FIG. 6 is a top plan view thereof; and,

FIG. 7 is a bottom plan view thereof.

All features illustrated in phantom line are expressly disclaimed and form no part of the claimed design.

1 Claim, 6 Drawing Sheets# US D610,766 S
